UNITED STATES PATENT OFFICE

EDWARD B. MALLORY, OF TENAFLY, NEW JERSEY

DESIGN FOR A REFRIGERATOR UNIT

Application filed February 26, 1930. Serial No. 34,657. Term of patent 14 years.

To all whom it may concern:

Be it known that I, EDWARD B. MALLORY, a citizen of the United States, residing at Tenafly, in the county of Bergen and State of New Jersey, have invented a new, original, and ornamental Design for Refrigerator Unit, of which the following is a specification, reference being had to the accompanying drawing, forming a part thereof.

The figure is an elevational view of the article, showing my new design. The article shown in the drawing is circular in contour.

I claim:

The ornamental design for a refrigerator unit as shown and described.

EDWARD B. MALLORY.
